(57) **CLAIM**

We claim the ornamental design for a holster, as shown and described.

DESCRIPTION

FIG. 1 is a left, rear, top perspective view of a holster showing our new design; and,

FIG. 2 is a right, rear, top perspective view of the holster of FIG. 1.

The bottom view is omitted and forms no part of the claimed design.

The front view is omitted and forms no part of the claimed design.

Broken lines shown in the drawings illustrate structure or features which form no part of the claimed design.
